UNITED STATES PATENT OFFICE.

JOHN HARRIS, OF CLEVELAND, OHIO, ASSIGNOR TO THE METALS WELDING COMPANY,
OF CLEVELAND, OHIO, A CORPORATION OF OHIO.

BLOWPIPE.

1,044,651.

Specification of Letters Patent. Patented Nov. 19, 1912.

Application filed September 29, 1909. Serial No. 520,121.

To all whom it may concern:

Be it known that I, JOHN HARRIS, a citizen of the United States, residing at Cleveland, in the county of Cuyahoga and State 5 of Ohio, have invented a certain new and useful Improvement in Blowpipes, of which the following is a full, clear, and exact description, reference being had to the accompanying drawings.

10 This invention relates to blow-pipes, and more especially to blow-pipes that are used for burning oxygen and acetylene.

Among the objects of the invention are the provision of a blow-pipe which shall 15 be reliable in operation and in which the tip will not melt or oxidize the orifice and thus produce stoppage or distortion of the flame; also the provision of a blow-pipe wherein the proper mixing of the gases will 20 be effected and in which the danger of leakage both internally between the gas passages and externally to the exterior of the blow-pipe shall be a minimum; the provision of a device of this nature wherein the 25 tip may be quickly changed to adapt the device for different varieties of work; the provision of a device of this nature in which the danger of the flame snapping back shall be at a minimum; while other objects and 30 advantages of the invention will become apparent as the description proceeds.

Generally speaking my invention may be defined as consisting of the combinations of parts recited in the claims hereto annexed 35 and illustrated in the accompanying drawings, wherein:

Figure 1 represents a longitudinal sectional view taken through a blow-pipe and its handle; Fig. 2 is a sectional view corresponding to line 2—2 of Fig. 1; Fig. 3 is a sectional view corresponding to line 3—3 of Fig. 1; and Fig. 4 is a side elevation of one of the tubes which is located in the acetylene conduit and which serves to prevent the propagation of flame therethrough. 45

Describing the parts by reference characters, 1 denotes the body or head section of the blow-pipe proper, said section consisting of a hollow casting of suitable metal, 50 preferably brass. This casting has a closed rear end 2 and an open front end 3, and is formed intermediate of its ends with an inwardly projecting annular portion 5, here shown as provided with internal screw threads. 55

The side of the section 1 is provided with a neck 6, said neck being provided with two passageways 7 and 8 communicating with the interior at opposite ends of the annular portion 5. The outer end of the neck 6 is 60 provided with an annular groove having therein a packing 9, of asbestos or similar material. This groove is for the reception of the end of a casing through which acetylene is supplied to the passageway 8. 65

The nozzle 10 is provided with a longitudinal bore 11 for the passage of the mixed gases and is connected to the section 1. This nozzle is preferably of brass, except as to the tip thereof, and comprises a tubular 70 body whose rearward end is adapted to enter the section 1 and whose forward end projects forwardly from said section to convey the mixed gases to the point of use. The rearward end of said nozzle is indicated generally by the reference character 12 and has an annular portion 12^a adapted to engage the annular portion 5 of the section 1. The portion of the casing and of the nozzle immediately forward of these 75 annular portions are formed so as to define an annular chamber 13, which chamber is in communication with the passageway 8. The formation of the easing and of the nozzle at the rear of the annular portion is 80 such as to provide a chamber 14 which is in free communication with the passageway 7. In the embodiment illustrated, the chamber 13 has been provided by forming an annular exterior groove in the portion 90 12 of the nozzle between the annular engaging portion and the end of the section 1; it is obvious, however, that this chamber could be provided in other ways. Likewise, the annular engaging portion 12^a of the nozzle 95 extension is illustrated as provided with screw threads for engagement with the threads of the portion 5 whereby the nozzle is secured to the section; it is obvious that this securing might be effected in some other manner. Moreover, the nozzle herein illustrated is provided with a flange 15 at the forward end of the extension 12 adapted to engage the forward end of the section 1 and to close the chamber 13; it is obvious 100 that this closure could be effected otherwise.

The nozzle extension 12 is formed with an axial recess 16, forming a continuation of the bore 11, and the wall of this recess is formed with ports 17 whereby the same is 110

put in communication with the chamber 13 at the forward end of the section. Mounted in the rearward end of this recess is a second nozzle 20 having therein a longitudinal bore 21 communicating with the chamber 14 and substantially aligned with the bore 11 of the first nozzle. The forward end of the second nozzle is preferably tapered so as to overhang the ports 17 and is spaced from the bottom of the recess 16 so as to permit communication between the ports 17 and bore 11.

In the present embodiment the rearward end of the recess 16 is shown as enlarged somewhat and provided with internal screw threads 22 adapted for engagement with similar screw threads formed upon an enlarged part of the second nozzle 20. Forward of this enlarged portion the nozzle 20 is illustrated as reduced in size sufficiently to cause it to fit slidably within the main part of the recess so as to insure the proper positioning and centering of its discharge end irrespective of its adjustment along the recess.

The front or main portion of the nozzle projects forwardly from the section 1 and is here shown as provided at its extremity with a frusto-conical recess 23, in which is fitted a tip 24, said tip having a bore 25 constituting an extension of the bore 11, and also having a flange 26 adapted to abut against the front end of the nozzle. This tip may be of nickel if desired which is found to exhibit peculiar advantages in connection with blow pipes of this character, although any desired material may be employed within the scope of my present invention. A washer 27 may, if desired, be interposed between the flange 15 and the front end of the section 1.

For conveying the gases to the proper chambers of the casing I may employ the construction illustrated in the lower part of Fig. 1, wherein I have shown a tubular casing 30 having one end introduced into the annular groove hereinbefore mentioned and having its other end closed by a suitable cap 31. Introduced within this casing I have illustrated a plurality of concentric metallic tubes 32 the peripheries whereof are formed with shallow helical grooves 33, whereby acetylene or other inflammable gas may be conducted from one end of the casing to the other without the possibility of flame striking back therethrough. The innermost of these tubes may be connected with the passageway 7 by means of a suitable connection 34 threaded therein, and the opposite end thereof may be provided with a connection 35 extending through an aperture in the cap 31. In the present embodiment the connections 34 and 35 are secured rigidly to the ends of the same tube 32, and the casing 30 is secured in connection with the section 1

by means of a nut 37 screwed upon the threaded end 36 of the connection 35, suitable packing glands being employed to prevent the leakage of gas. A valved nipple 38 may be employed to conduct oxygen or like gas to the connection 35, while a similar nipple 39 may be employed for conducting acetylene or like combustible fluid to the interior of the casing 30, the cap 31 being illustrated here as provided with a socket for the reception of such nipple. I have shown the interior of the innermost tube 32 as filled with fibrous material 40, such as asbestos, partly for the purpose of preventing the propagation of a flame therethrough in case a mixture of acetylene should for any reason be forced back into the oxygen conduit, and partly to cause the oxygen to pass in close contact with the tube 32 so as to abstract heat therefrom and cool the acetylene. It will be understood, however, that the particular construction of the chamber 30 and its associated parts form no part of the present invention, which is directed solely to the construction of the blow pipe head. Likewise it will be understood that while I have described in detail the construction of this head, I do not propose to be limited to such details, except as the same may be positively included in the claims hereto annexed or may be rendered necessary by the prior state of the art.

Having thus described my invention, what I claim is:

1. In a blow pipe, the combination of a section having a bore, said bore being threaded intermediate of its ends and said section having inlet ports communicating with said bore on opposite sides of such threaded portion, a nozzle having a chamber and having a threaded portion adapted to be threaded into the corresponding portion of the section bore, said nozzle being provided with a jet passage extending forwardly from said chamber, and a second nozzle threaded into the rear portion of the first nozzle and having a tapered end cooperating with said jet passage, said second nozzle being provided with a bore communicating with the space at the rear of the thread in the section bore, and one or more ports placing said chamber in communication with the section bore in front of such thread.

2. In a blow pipe, the combination of a section having a longitudinal bore and provided intermediate of the front and rear of said bore with an inwardly projecting threaded portion and having inlet ports communicating with said bore at opposite ends of such threaded portion, a nozzle having intermediate of its ends a flange and provided with a chambered extension at the rear of said flange, said extension being provided with ports communicating with said

chamber and said nozzle having a jet passage extending forwardly from said chamber, the rearward portion of said extension being enlarged and provided with a thread 5 adapted to engage the threaded portion of said section, said extension also having internal threads at its rearward portion, and a second nozzle having a bore and threaded into the rearwardly projecting portion of 10 the first nozzle and having its front portion extending into said chamber in the rearwardly projecting portion of said first nozzle.

3. In a blow pipe, the combination of a 15 section having a longitudinal bore and provided intermediate of the front and rear of said bore with an inwardly projecting threaded portion and having inlet ports communicating with said bore at opposite 20 ends of such threaded portion, a nozzle having a rearwardly extending threaded portion adapted to engage the threaded portion of said section, said rearwardly extending portion being hollow so as to form a chamber, the wall of said chamber being provided 25 with ports communicating with the section bore in front of said threaded portion and said nozzle having a jet passage extending forwardly from said chamber, and a second 30 nozzle secured in the rearward end of said chamber and having a bore communicating at its rear end with the portion of said section bore at the rear of said inwardly projecting threaded portion.

35 4. In a blow-pipe, the combination of a section having a longitudinal bore and an inwardly projecting threaded portion intermediate of the ends of said bore, said section being provided with an inlet port communicating 40 with said bore at opposite sides of said threaded portion, a nozzle having a threaded portion adapted to engage said first threaded portion, the adjacent surfaces of said section and of said nozzle being so 45 formed at a point forward of said threaded portion as to provide an annular chamber therebetween, means for closing the forward end of such chamber, said nozzle having a longitudinal bore and a recess with which 50 said bore communicates, the wall of said recess being formed with lateral ports which communicate with said annular chamber, and a second nozzle mounted in the rearward end of said recess and having a longitudinal bore therethrough substantially in 55 alignment with the bore in said first nozzle and communicating with the chamber at the

rear of said threaded portion, the forward end of said second nozzle being spaced from the bottom of said recess. 60

5. In a blow-pipe, the combination of a hollow section having an inwardly projecting annular portion intermediate of its ends, a nozzle having an annular portion adapted to engage said first annular portion, the adjacent surfaces of said section and of said nozzle being so formed at opposite sides of said annular engaging portions as to provide a pair of separated chambers and the wall of said section being formed with an inlet port 70 communicating with each of said chambers, said nozzle having a longitudinal bore and a recess with which said bore communicates, the wall of said recess being formed with lateral ports which communicate with the 7 forward one of said chambers, and a second longitudinally bored nozzle mounted in the rearward end of said recess and communicating with the chamber at the rear of said threaded portion, the forward end of said 80 second nozzle being spaced from the bottom of said recess.

6. In a blow-pipe, the combination of a hollow section having a pair of inlet ports at longitudinally spaced points thereof, a 85 tubular nozzle having its rearward end adapted to enter said section and its forward end to project therebeyond, the portions of said nozzle and of said section lying between said inlet ports being formed for interengagement whereby communication between the ends of said section is prevented, and the adjacent walls of said section and nozzle being formed at each side of said interengaging portions to provide chambers, one of 90 which is in communication with each of said inlet ports, the rearward portion of the bore of said nozzle being enlarged to form a recess and the wall of said nozzle having ports whereby said recess is put into communication with one of said chambers, and a second nozzle secured in said recess at the opposite side of said ports from the bore of 95 said first nozzle, said second nozzle also having a bore substantially aligned with the bore in said first nozzle and communicating with the other of said chambers. 100 105

In testimony whereof, I hereunto affix my signature in the presence of two witnesses.

JOHN HARRIS.
